(57) CLAIM

The ornamental design for a pocket cap, as shown and described.

DESCRIPTION

FIG. 1 is a right side perspective view of a pocket cap showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is an inside view thereof showing a mesh pocket. The broken lines on claimed surfaces depict stitching and form no part of the claim.
